(57) **CLAIM**

The ornamental design for a lighter assembly, as shown and described.

DESCRIPTION

FIG. 1 is a perspective view of the lighter assembly showing my new design;

FIG. 2 is a perspective view thereof from another angle;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated with numeric 9 in FIG. 1;

FIG. 10 is an enlarged view of a portion indicated with numeric 10 in FIG. 1;

FIG. 11 is an enlarged view of a portion indicated with numeric 11 in FIG. 1;

FIG. 12 is an enlarged view of a portion indicated with numeric 12 in FIG. 1;

FIG. 13 is an enlarged view of a portion indicated with numeric 13 in FIG. 1; and,

FIG. 14 is an exploded view thereof.

The dot-dash broken lines are for purpose of annotating the enlarged views only and form no part of the claimed design. The evenly-spaced broken lines depict portions of the lighter assembly that form no part of the claimed design.

1 Claim, 14 Drawing Sheets
